US00D840618S

(12) **United States Design Patent** (10) Patent No.: **US D840,618 S**
Kim et al. (45) Date of Patent: **** Feb. 12, 2019**

(54) **ROBOT FOR CLEANING**

- (71) Applicant: **LG ELECTRONICS INC.**, Seoul (KR)
- (72) Inventors: **Seongmin Kim**, Seoul (KR); **Jaeyoung Kim**, Seoul (KR); **Hyeonjeong An**, Seoul (KR); **Myungwhoon Lee**, Seoul (KR)
- (73) Assignee: **LG ELECTRONICS INC.**, Seoul (KR)
- (**) Term: **15 Years**
- (21) Appl. No.: **35/503,959**
- (22) Filed: **May 16, 2017**
- (80) **Hague Agreement Data**
- Int. Filing Date: **May 16, 2017**
 Int. Reg. No.: **DM/096829**
 Int. Reg. Date: **May 16, 2017**
 Int. Reg. Pub. Date: **Nov. 17, 2017**

(30) **Foreign Application Priority Data**

- Nov. 30, 2016 (KR) 30-2016-0058000
